POLISHING MACHINE

Hans Christian Arge and Herman Tischer,
New York, N. Y.

Application May 25, 1934, Serial No. 727,478

3 Claims. (Cl. 51—170)

The invention refers to polishing machines, in particular to such machines, which are adapted to do polishing or similar preparatory work on larger, more or less flat surfaces, such as for instance, ceilings, floorings and walls in buildings, and also larger pieces of furniture, automobile bodies, and other similar work in different industries.

The hand-polishing of larger articles or larger surfaces is extremely tiresome and difficult work. There are already known devices or tools for carrying out part of such polishing work automatically by machines, some of such polishing machines or tools comprising a polishing pad at the end of a flexible rotating shaft, which pad the workman may apply to different places on the surface to be polished. The polishing machines or devices of this kind can work only on a very small part of the surface at a time, and furthermore there are limits as to their usefulness, owing to the fact, that the disk-shaped rotating pad cannot be applied into hollow corners of the room or article to be treated.

The object of the present invention is to provide a comparatively simple but nevertheless extremely efficient polishing device or polishing machine, which is adapted to do the polishing or similar work in the above said different fields of its application. In this respect it is an essential point of the present invention, that the machine or device of my design will carry out the greater part of the movements of the polishing pads in an automatic manner, so that the workman has only to direct the polishing tools proper to those points which need the treatment, but he has not to carry out any longer the extremely tiring quick rubbing movements of sanding, polishing or other working on the workpiece.

It is further the object of the present invention, to provide a polishing machine or polishing device, in which the tools proper for treating the workpiece may be exchanged easily and such special tools may be inserted, which fit the particular kind of work to be done.

Furthermore it is an important feature of my new and improved polishing machine or device, that it can do polishing work not only on flat surfaces, such as slabs or the walls of buildings, but likewise on more or less curved or uneven surfaces, such as they are for instance on the body and other parts of automobiles. The polishing tool machine or device of the present invention may be adapted to the special needs of different industries, and to the working on different materials such as stone, wood, metal, etc. In par-

ticular this new device for polishing and similar work may be a portable hand-tool to be carried about and to be pressed against the article to be treated, or it may be a temporary or permanently stationary fixture on the working bench in a workshop. The mechanical power applied to the polishing or other tools may be supplied by an electric motor provided on the device itself, or by a flexible shaft or any other suitable transmission from any stationary source of energy. These and other features of the invention will become more clear in the course of the following detailed description of some preferred embodiments of my invention; this detailed description having reference to the accompanying drawing, in which:

Figures 1 to 4 show a preferred embodiment; Fig. 1 being a longitudinal section; Fig. 2 a partly sectioned end-view; Fig. 3 being a top-view, and Fig. 4 being a bottom view of the polishing machine.

Referring now in particular to the first embodiment of the invention, 11 is an approximately rectangular flat casing, containing the main parts of the gearing and closed at its lower side by the cover or lid 12. Opposite to the lid, the top of the casing 11 is provided with handles for the device, these handles being fixed with four legs 13 at the four corners of the casing, and having two hand-grips 14, extending longitudinally over the casing 11, whereas the middle part between the two grips 14 is formed by a ring or clamp 15, which embraces the electric motor 16. The shaft of this electric motor extends into the casing 11 and carries a small pinion 17, which pinion, by means of the two intermediary gears 18, drives the two big toothed wheels 19. The lid or cover 12 at the lower side of the casing 11 is provided with two long slots 20 extending from two diagonally situated corners of the casing along the longer sides of the lid or cover for about one-half of its length.

These slots 20 serve as guideways, in which the carriers of the polishing tool may reciprocate, each carrier being actuated by a connecting rod 21, the two ends of which rod 21 are pivoted to the tool carrier and to the pin 22 on one of the two toothed wheels 19 respectively. Each tool carrier, as shown in the Fig. 1, consists of a slightly conical truncated block 23, the upper end of which reaches through the slot 20 and it is pivoted to the connecting rod 21, so that the rotation of the wheel 19 will cause the reciprocating sliding movement of the tool 23. The lower end of the tool carrying block 23 forms a double-shelled thrust-bearing for the ball-shaped

head 24 and for the stem of the tool holder, the flat foot plate 25 of which tool holder carries the preferably exchangeable polishing pad 26 of rectangular shape. The ball-joint connection 24 between the tool carrier 23 and the polishing tool 26 allows this tool to adjust itself automatically to the surface of slightly curved work-pieces, such as, for instance, an automobile body, and to change its adapting inclination any moment, whilst the tool is moved over the curved surface of the work-piece. A spirally coiled spring 27, abuts with its two ends against the tool-holder plate 25 and the foot of the tool carrier 23 respectively, so as to secure a perfect contact between the whole face of the pad 26 and the work-piece to be treated. It has been found, that the working of this coiled spring 27 is most satisfactory, if it does not make circular turns, but turns, which have the shape of flattened loops as it is indicated in Fig. 1.

From the foregoing description of the parts the use and operation of this polishing tool will be easily understood to be as follows: Electrical current, fed from a suitable source of energy through the cable 28 to the electric motor 16, will cause rotation of the pinion 17 keyed to the motor 16, and this rotative movement is transferred to the two toothed wheels 19. The eccentric pin 22 on each toothed wheel and the connecting rod 21 pivoted to it change this rotative movement of the wheel 19 into a longitudinally reciprocating movement of the tool carrier 23 along its slot 20. Therefore the two polishing pads 26 will carry out reciprocating movements on the work-piece against which they are pressed, and the workman has only to hold the whole device at the grips 14 and to press it slightly against the work-piece. If the surface of the work-piece to be treated, is rather large, the workman moves the whole device by the grips 14 slightly over the whole surface of the work-piece, thus covering

by and by the whole surface of this work-piece and carrying out the polishing or other treatments of it.

We claim:

1. A machine for carrying out polishing and similar work, comprising in combination: a rectangular flat boxlike frame; an electric motor mounted centrally on the top of the said frame; a motor-shaft extending into the said boxlike frame; two handles extending lengthwise over the top of the said frame from the middle of the motor-housing to opposite ends of the frame; two large wheels in the boxlike frame at the two sides respectively of the motor-shaft; gearings connecting the said shaft with the said wheels; a lid covering the open side of the boxlike frame; two slotted guideways in the lid, extending along the two longer sides of the lid from two diagonal corners to beyond the middle of the length of the lid; blocks mounted slidably within said guideways; pins in the said wheels and connecting rods between the pins and the said blocks; and tool-carrying means on the said blocks, adapted to be set into any inclination to the basic plane of the machine.

2. A machine as claimed in claim 1, in which the outer ends of the two handles branch into four feet, which are fixed at the four corners of the boxlike frame.

3. A machine as claimed in claim 1, in which the tool-carrying means consist in stilted tool-holders, ball-jointed connections between the stilted ends of the tool-holders and the blocks carrying the tool-holders, rectangular pads fixed at the other ends of the tool-holders, and helical springs surrounding each one of the said blocks and the tool-holder jointed to it over their whole combined lengths from the foot of the block to the pad at the end of the tool-holder.

HANS CHRISTIAN ARGE. 403
